KEYLESS LOCK

Edward M. Miller, Kent, Ohio, assignor to The
J. B. Miller Keyless Lock Co., Kent, Ohio, a
corporation

Application August 12, 1931. Serial No. 556,701

6 Claims. (Cl. 70—112)

In standard forms of keyless or so-called "combination" locks, there have been certain disadvantages which the present invention is designed to overcome.

For example, in the standard combination lock construction, it is usual to provide upon a rotating disc located within the lock casing, a plurality of lugs or segments of varying configurations and positions, which, under a given sequence of operating conditions, will actuate an arm which in turn operates a catch member to release the shackle of the lock.

From the nature of the construction of the mechanism, this arm is loosely pivoted to the pivoted end of the lock shackle, with the result that if the lock be inverted, the arm will drop into the position which it should take in operating the aforesaid catch so that it is possible when in such inverted position by simply turning the disc 20 in the same direction to have one of the lugs upon the disc come in contact with the pin usually carried on the arm so as to depress the arm and release the catch without utilizing any combination. It, therefore, becomes frequently easy 25 for an unauthorized person knowing the trick of operating the lock in this manner to open the lock and gain access to whatever is intended to be protected thereby.

Furthermore, in standard lock constructions of 30 this character, it is sometimes easy for unauthorized individuals having practice in the opening of locks of this character to be able through their sense of touch to work out the combination of such a lock.

Also, it is possible by one having an ear sufficiently trained to ascertain the character of clicks in the usual lock construction when the combination of the lock is reached, and thus be able 35 to open the lock.

Again, it is sometimes customary for individuals to "set" the standard lock by first operating the combination and releasing the shackle thereby, and as the shackle is released by turning the operating disc in the proper direction, usually 40 backwards, it is possible to subsequently release the shackle by simply turning the disc back a comparatively short distance to its unlocking position, so that the lock may be operated without going through the entire cycle of combinations, thus 45 rendering the lock easy of operation by an unauthorized individual knowing this tendency to leave the lock in a set position.

It is also easy in many of the forms of the standard lock constructions for an unauthorized 50 person to open the lock by operating the arm

through the insertion of a wire or other instrument, and thereby pressing the arm against the lock catch to release the shackle.

The present invention deals with a keyless lock construction which avoids the aforesaid disadvantages in the standard construction of locks of this character, which maintain a simple construction.

The invention will be more readily understood by reference to the accompanying drawings, in which:

Figure 1 is a view through the casing of an improved lock made in accordance with this invention, showing details of the mechanism.

Figure 2 is a fragmentary view illustrating an improved shackle as employed on the locks made in accordance with this invention.

Figure 3 is a perspective view of such a shackle.

Figure 4 is a perspective view of an improved disc used in locks formed in accordance with this invention.

Figure 5 is a view similar to Figures 1 and 2 showing the interior construction of a still somewhat different form of lock.

Figure 6 is an outside view showing in elevation one of the improved locks of this invention.

Figure 7 is a view of still another somewhat different form of lock construction as embodied in this invention; and

Figure 8 shows in elevation, the lock of Figure 8 looking on the outside of the casing and showing the numbered dial employed for indicating the combination of this form of lock.

Figure 9 is a partial view of the lock casing and the shackle illustrating the relation between the lock casing and the shoulder on the shackle.

It is known that in "combination" padlocks the construction is such that the shackle 6 of the lock is pivoted to the casing 1 at one end of the shackle as at 7 and is provided at the other end 95 with a projection 8 for interengaging with a latch member 9 positioned within the casing of the lock and pivoted thereto as at 10 and which is maintained in proper position by the pressure of a suitably arranged spring 11, which normally 100 maintains an arm formed on the latch in engagement with the projection 8 on the free end of the shackle.

Release of the latch member is accomplished by suitable manipulations of a disc 2 rotatably mounted within the casing and operable from outside of the casing. This disc is provided with peripheral notches at spaced points along the disc, and is provided on its interior surface with a plurality of lugs 4, through the proper combi- 110

nation of which the lock may be opened in a manner known in the art.

The members 4 are differently shaped and are arranged in different positions relatively to the periphery of the disc 2 so that through proper manipulation of this disc with the members, a pin 15 projecting from an arm 12, which is pivoted to the casing at 13, will be engaged to press the pin and the end 14 of the arm 12 outwardly against the latch 9 to depress the latch out of engagement with the shackle 6 so as to release the shackle.

To avoid the possibility of unauthorized opening of the lock by the various tricks, previously referred to, which may be successfully resorted to in the standard lock construction, the construction of Figure 1 is provided. This construction simply consists in providing the disc 2 with a projecting flange 16, so that the pin 15 of the arm 12 will always be inside of the flange 16, and therefore, held away from the catch 9 until the proper combination has been reached, when it will drop out through the opening 17 between the flange and one of the members 4 to thereby release the shackle in the aforesaid manner; the pin 15 then bearing against the outside of the flange 16. The provision of this flange around the periphery of the disc 2 will prevent the opening of the lock in the aforesaid manner.

It has already been pointed out that in locks of the previous standard construction, it has been possible to operate the arm 12 by inserting a wire or some similar member through the shackle apertures in the housing, but this is prevented in the present instance by providing the latch end of the shackle with an upstanding shoulder portion or rib 18, which will effectively prevent access to the latch 9 or arm 12 by any such means, and also by providing the pivoted end of the shackle with a shoulder 19, also an upstanding shoulder, all possibility of access to the arm 12 from this position will be avoided.

It will be clearly seen from the figures that shoulders 18 and 19 are higher than the areas of the shackle adjacent them.

Thus the present invention has been further designed to render substantially totally inaccessible the interior mechanism of a lock of this type without necessitating the destruction of the lock.

In order to overcome the discovery of the combination of the lock through the sense of touch, the disc 2, is provided with a knurled surface edge 20 against which the spring 21 is adapted to ride. This provision of the knurled surface of the edge prevents an individual from feeling the friction between the extensions 4 and pin 15, which friction might indicate to a person with a sufficiently delicate touch the position of the arm 12 and thus enabling him to open the lock.

In Figure 5 there is represented a construction which will prevent the lock from being opened without using the full combination. In this construction, the disc 2 is provided with a bifurcated member 4b and has also the flange 16 of the construction previously described, there being positioned in the casing adjacent the latch end of the shackle 6 an arm 22 under pressure of spring 23, the arm 22 being pressed normally by the spring 23 against the catch end 8 of the shackle 6. This arm 22 has an inwardly projecting portion 24 which is adapted to engage a bifurcated member 4b carried on the disc, as aforesaid. By this construction, when the shackle 6 has been unlocked, and the arm 12 positioned as shown in Figure 5, it will not be possible to rotate the disc

2 in a backward direction because of the inter-engagement of the member 24 with the bifurcated member 4b on the disc, thus locking the said disc against clockwise rotation.

In order to lock the shackle 6, therefore, the disc 2 must be moved in a counter clockwise direction, which will result in the arm 12 assuming the interior position relatively to the flange 16, as soon as an opening in this flange comes into registry with the pin 15 in the arm 12. When this arm drops down in the lower position shown in Figure 7, of course, the full combination must be operated in order to reopen the lock.

In Figure 6 the exterior of the lock is shown in elevation with the operating handle or knob 25 provided with an upstanding lug 26 serving as an indicator for the start of the combination operations, in connection with the arrow 26a.

If it is desired to omit the audible clicks usually present in the standard combination lock construction the construction in Figure 7 may be had, wherein the notches are omitted so that the spring 21 rides continuously without interruption along the outer rim of the disc 2. In this connection to guide the combination operations, there is provided a numbered dial 27, as there is no audible click in this instance, and since the stop member is omitted in these improved constructions, it will be seen that there is rendered a lock in which the possibility of its being opened by an unauthorized person is reduced to an absolute minimum.

It will be apparent that various details in the specifically illustrated and designed forms of the invention may be changed without departing from the spirit of this invention, and that such changes will become obvious to one skilled in this art.

It will, therefore, be understood that it is intended and desired to embrace within the scope of this invention, such modifications and changes which may be necessary to adapt it to varying conditions and uses.

Having thus described my invention, what I claim as new and desire to secure by Letters Patent of the United States, is:—

1. A lock comprising the combination with a casing, having the usual shackle, latch, and actuating arm therefor, of a rotative disc within the casing having a plurality of combination members thereon, the said disc being provided with an upstanding flange extending substantially around the disc but spaced sufficiently from the periphery thereof to prevent engagement of the actuating arm with the latch except through proper operation of the combination members on the disc.

2. A lock comprising the combination with a casing having the usual shackle, latch and actuating arm therefor, of a rotative disc within the casing having a plurality of combination members thereon, means on the disc for preventing engagement of the actuating arm with the latch except through proper operation of the combination members on the disc and a depressible interlocking member adapted to engage one of the combination members on the disc and to interlock therewith upon release of the shackle to prevent further operation of the disc in but one direction.

3. A lock comprising the combination with a casing having the usual shackle, latch and actuating arm therefor, of a rotative disc within the casing having a plurality of combination members thereon, means on the disc for preventing engagement of the actuating arm with the latch except through proper operation of the combination members on the disc and a depressible interlocking member adapted to engage one of the combination members on the disc and to interlock therewith upon release of the shackle to prevent further operation of the disc in but one direction.

tion members on the disc, and an inter-locking member adapted to engage the disc and to interlock therewith upon release of the shackle to prevent further operation of the disc in but one direction, the said member being held in depressed position by the shackle while the shackle is locked.

4. A lock comprising the combination with a casing having the usual shackle, latch, and actuating arm therefor, of a rotative disc within the casing having a plurality of combination members thereon, one of the said members serving as a stop member and an interlocking member adapted to engage the said stop member on the disc upon release of the shackle to prevent further operation of the disc in but one direction.

5. A lock comprising the combination with a casing having the usual shackle, latch and actuating arm therefor, of a rotative disc within the casing having a plurality of combination members thereon, one of the said members serving as a stop member, an upstanding peripheral flange

on the disc for preventing engagement of the actuating arm with the latch except through proper operation of the combination members on the disc and an interlocking member adapted to engage the said stop member on the disc upon release of the shackle to prevent further operation of the disc in but one direction which operation of the disc will cause the said actuating arm to drop behind the said peripheral flange thereby preventing reopening of the lock except through the operation of the complete combination.

6. A lock comprising a casing having the usual shackle, latch and actuating arm therefor, the said shackle being provided with raised shoulders to prevent access to the latch and operating arm from outside of the casing, the said shoulders being on the interior of the casing when the shackle is in locking position, the said shoulders blocking introduction of any unlocking instrumentality through the casing to the latch.
